3 Claims. (Cl. 196—52)

1

This invention relates to the removal of carbonaceous deposits from tubes. In one of its more specific aspects it relates to removal of carbonaceous deposits from tubes in which hydrocarbon oil has been heated in a process for catalytically converting hydrocarbon fluids.

Hydrocarbon fluids, when subjected to elevated temperatures, decompose in part to carbon, coke, or other carbonaceous materials. In heating hydrocarbons to elevated temperatures within a furnace, carbonaceous deposits gradually accumulate on the inner walls of the furnace tubes. The accumulated carbonaceous deposit eventually impairs the most efficient furnace operation by reducing the cross sectional area and consequently the flow of the hydrocarbon fluids. Furthermore, such carbonaceous deposits reduce the efficiency of the furnace operation by reducing the rate of heat transfer. This difficulty is especially significant in a process wherein heavy oils are heated, a larger quantity of carbon, coke, and other carbonaceous material consequently being deposited on the inner walls of the furnace tube.

The accumulation of a deposit of carbonaceous material, therefore, necessitates its removal and involves taking the tube out of service for cleaning. Various methods proposed for removal of the carbonaceous deposits from the inner walls of heating tubes include oxidation means employing oxygen, or an oxygen-containing gas, and such oxidation means supplemented with mechanical means for dislodging the remaining unburned carbonaceous deposit. In practicing these methods, it is known that the employment of an oxidation means, can result in temperatures harmful to the tubes. The employment of a mechanical means, supplementary or otherwise, involves an additional loss of time required for the tube to cool to a temperature at which the equipment can be handled. Such handling involves the removal of headers, return bends, and the like, and because of the frequent handling required, and mechanical abrasive effect on the tubes, effects a shorter life of the mechanical parts.

This invention has for an object a method for removing carbonaceous matter deposited on the inner walls of tubes in a heater employed in a catalytic process for conversion of hydrocarbon oils, whereby the removal of the carbonaceous deposits can be effected without interruption of the continuously operating catalytic conversion process.

A further object of the invention is the re-

2

moval of carbonaceous deposits from the inner walls of tubes in a heater employed in a catalytic process for conversion of hydrocarbon oils whereby the removal of said carbonaceous matter can be effected by a novel combustion method wherein severe temperatures, harmful to the tubes, are avoided.

I have found, when passing a hydrocarbon oil over a fixed bed of granular bauxite catalyst and cracking same and subsequently regenerating said fixed catalyst, i. e. removing carbon deposited on the surfaces thereof by means of combustion supported by a mixture of steam and an oxygen-containing gas, that the oxygen content of the effluent gases initially is substantially nil, with said gas consisting essentially of nitrogen, carbon monoxide, carbon dioxide, and steam, until the duration of the said regeneration is about one-half elapsed, the oxygen content subsequently gradually increasing by virtue of oxygen breaking through the incompletely regenerated catalyst, and continuing to increase until at the termination of said regeneration, said oxygen content is approximately 18 to 20 per cent based on the dry gas effluent.

In accordance with this invention, carbon, coke, or other carbonaceous materials deposited on the inner walls of the tubes within a heating furnace in a process for catalytically cracking hydrocarbon oils, are removed by combustion or a "burn-out" supported by an oxygen-containing gas and diluent comprising the effluent gas of the catalyst combustion regeneration, supplemented when desired by another oxygen-containing gas and another diluent, the catalyst combustion regeneration gas comprising a mixture of steam, air, and/or another oxygen-containing gas.

As shown in the drawing, the hydrocarbon oil is passed to a primary preheater wherein it is heated to a temperature slightly lower than that at which formation and deposition of carbonaceous material initially occurs, thereby preheating the hydrocarbon oil to a maximum allowable temperature and avoiding a deposition of carbonaceous material. The primary preheater effluent is passed intermittently and alternately to one and the other of two secondary heaters wherein said primary preheater effluent is heated to temperatures required by the subsequent catalytic conversion process, but which are higher than those at which formation and deposition of carbonaceous materials initially occurs, consequently accumulating a carbonaceous deposit on the inner walls of the secondary heater tubes thereby impairing hydrocarbon fluid flow and

efficiency of heat transfer through the tube walls. The primary preheater effluent is passed to one of two secondary heaters until an accumulation of carbonaceous materials impairs operation. The flow of the primary preheater effluent is then switched to the other of the two secondary heaters thereby effecting a continuation of the secondary heating step without interruption. Removal of the carbonaceous deposits from the heater tubes previously serving to heat the effluent of the primary preheater is effected simultaneously by combustion supported by effluent gas of the catalyst regeneration, supplemented if desired, by another oxygen-containing gas and/or another diluent. The oxygen content of said gas effluent of the catalyst regeneration is initially nil and subsequent to about half the duration of the catalyst regeneration is in the order of less than two per cent but steadily increases thereby comprising a means for gradually increasing the oxygen content of the combustion supporting gas and for control of the combustion temperature during removal of said carbonaceous matter. Effluent gas of the catalyst regeneration can be supplemented with another oxygen-containing gas and/or another diluent, when desired, effecting thereby a further control of said combustion temperature.

The intermittent and alternating operation abovedescribed, provides a method for continuing simultaneously the removal of said carbonaceous deposits from tubes in the secondary heating zone and the secondary heating of the primary preheater effluent.

The aforescribed process provides advantages yet unmentioned, for example, the process is especially advantageous in processing top crude or heavy gas oils and the like, wherein deposition of carbonaceous matter is greater than that effected when processing a relatively light oil, such as a gas oil having a gravity in the range of 35 or 40° API and an end point of 700° F.; the intermittent burn-out aforescribed prevents an accumulation of carbonaceous matter that normally would impair heater operation after an operating period approximating 8 to 12 hours. Another yet unmentioned advantage is an economic one, i. e. a reduced cost of burning out the heater tubes. The effluent catalyst regeneration gas provides a constant source of diluent at the proper temperature and pressure for the burn-out, and a source of oxygen for about half the duration of the catalyst regeneration at the proper temperature and pressure, eliminating to a great extent thereby, the cost of compressing air or another oxygen-containing gas and of generating steam or providing for another diluent for said burn-out.

The accompanying drawing illustrates by means of a diagrammatic flow sheet an arrangement of apparatus which can be used in the practice of a preferred form of my invention. The following discussion will also serve as an example of the invention.

Referring now to the drawing, the heavy residual hydrocarbon oil having a gravity in the range of 25 to 40° API and boiling at a temperature in the range of 500 to 1100° F. is charged to the primary preheater 9 through line 10 and heated to a temperature lower than that at which formation and consequent deposition of carbonaceous material occurs, said temperature being in the range of 600 to 900° F. In some instances higher temperatures would be permissible dependent upon the characteristics of the specific hydrocarbon oil charged. The preheated oil is

passed through effluent line 11 to either of secondary heaters 15 or 55. For example, the primary preheater effluent is passed through valve 12 and line 13 with valves 14 and 54 closed, to secondary heater 15 and heated therein to a temperature suitable for subsequent catalytic conversion and higher than that at which formation and consequent deposition of carbonaceous matter initially occurs, said temperature being in the range of 975-1150° F. and higher, depending on the characteristics of the specific hydrocarbon oil charged, and upon the severity of the cracking conditions required in the subsequent conversion step. The heated oil, primarily in the vapor phase, is passed from secondary preheater 15 through effluent line 16, valve 18 and line 20, with valve 17 closed, to hot oil separator 21 and any unvaporized oil or tarry material is discharged through line 22. The vaporous hot charge is then passed through the hot oil separator overhead line 23 and valve 24 to the catalytic conversion taking place in either catalyst chamber 31 or 43. For example, the hot vaporous oil from valve 24 is passed through line 25 and valve 27 with valves 28, 42, and 65 closed, and through line 30 to catalyst chamber 31. The conversion of hot hydrocarbon vapors takes place at a temperature in the range of 950-1000° F. or higher, and at a pressure in the range of 0-200 p. s. i., the actual cracking conditions depending upon the characteristics of the hydrocarbon charge stock, the extent of the conversion desired and, consequently, the severity of the conversion conditions required. The effluent of catalyst chamber 31 leaves through line 32, valve 33 with valves 34 and 45 closed, and line 36 to a separation means 37 for further handling such as fractionation, recycle, etc.

During the conversion, carbon is deposited on the surface of the catalyst, and after a period of time such as from 2 to 6 hours' continuous operation, an accumulation of said carbon impairs the activity of the catalyst, necessitating the removal thereof. At such a time as the catalyst activity is impaired the hot hydrocarbon vaporous feed to catalyst chamber 31 is switched to an active catalyst in catalyst chamber 43, and subsequent to purging with steam, regeneration of the spent catalyst in chamber 31 is initiated by means of combustion of the carbon deposits accumulated on the surface thereof, said combustion being supported by a mixture of steam and/or another relatively inactive diluent with an oxygen-containing gas, said mixture of steam and/or other relatively inactive diluent with an oxygen-containing gas being referred to hereafter as the catalyst combustion regeneration gas. The oxygen content of the effluent gas of the catalyst combustion regeneration is initially substantially nil and after about one-half of the duration of the regeneration, said oxygen content is in the order of less than 2%, gradually and progressively increasing until such a time as said removal of carbon is substantially completely effected, said oxygen content thereafter approximating 18-20%. This invention is concerned with the utilization of the above described effluent gas for the removal of carbonaceous deposits accumulated on the inner walls of the tubes in the secondary heaters above described.

Simultaneously with the aforescribed heating of the hydrocarbon oil in heater 15 and the subsequent conversion in catalyst chamber 31, is the reactivation of catalyst in conversion chamber 43, and the removal of carbonaceous deposits

from the inner walls of tubes within heater 55; said catalyst having served previously during a conversion progressing in chamber 43 and said secondary heater 55 having served previously to heat primary preheater effluent to conversion temperatures approximating 975-1150° F. as aforescribed. The inactive catalyst is reactivated by the introduction of catalyst combustion regeneration gas under conditions effecting the removal of said carbon, to said catalyst chamber 43 through lines 38 and 41 and valve 40 with valves 28, 39 and 42 closed, and removal of carbonaceous deposits from within heater 55 is effected by a burn-out, or combustion, supported by effluent gas of the catalyst regeneration taking place in catalyst chamber 43, and supplemented if desired with another oxygen-containing gas and/or another diluent, said effluent gas leaving catalyst chamber 43 through line 44 and valve 46 with valves 45 and 34 closed and through line 47 splitting in part to line 48 through valve 49 to spent gas stack 50 and continuing in remaining part to secondary heater 55 through line 47 and valves 51, 52 and 53 with valves 14 and 54 closed. The effluent of the burn-out progressing in secondary heater 55 leaves through lines 56 and 57 and valve 60 with valves 58 and 61 closed, to spent gas stack 50.

In the practice of this invention, temperature control of combustion during the burn-out of the secondary heaters is effected to a major extent by passing effluent gas of the catalyst regeneration through said heaters and to a minor extent by supplementing said effluent gas with another oxygen-containing gas and/or another diluent gas such as steam. Said effluent gas has an oxygen content of substantially nil during at least the first hour of the burn-out and comprises during a period thereof, a mixture of nitrogen, steam and carbon dioxide, thereby serving as a diluent of any supplementary stream of oxygen-containing gas that might be employed. The oxygen content of said effluent gas after a time, as aforescribed, becomes significant and gradually increases to a maximum, and during that period, said effluent gas functions as a source of both oxygen and diluent thereby gradually decreasing to substantially nil the quantity of supplementary oxygen-containing gas being utilized as aforescribed. It is possible that during the latter stages of said catalyst regeneration, at the time the oxygen content of said effluent gas approaches the aforesaid maximum of 18-20%, supplementary diluent would be utilized to maintain the proper ratio of oxygen and diluent required to avoid local overheating within said secondary heater and consequent harmful effects on the heater tubes. The employment of said supplementary diluent and oxygen-containing gas streams varies as a function of the coking characteristics, or tendency of the specific hydrocarbon oil charged to deposit carbonaceous materials. This is obvious as the quantity of deposited carbonaceous material within the heater determines the quantity of oxygen required for removal of same; said quantity of oxygen in turn determines the quantity of diluent required to maintain a minimum ratio of diluent and oxygen to safeguard against harmful effects to the coil resulting from local overheating as aforescribed. If the carbonaceous deposit can be removed by the oxygen and diluent comprising the effluent gas of the catalyst regeneration, within the desired duration, usually that of the catalyst regeneration period, no supplementary oxygen

gas would be required. Probably no supplementary diluent would be required.

When a heavy residual oil, i. e. one having a gravity in the range of 20-30° API and boiling in the range of 600-1000° F., has been charged to the secondary heaters it is advisable to initially employ supplementary oxygen-containing gas and subsequently employ supplementary diluent gas in order to effect complete removal of the consequent deposition of carbonaceous matter within the duration of the catalyst regeneration period, at the end of which, the removal of all carbonaceous deposits within the secondary heater would be complete.

- 15 When charging a hydrocarbon oil having a gravity in the range of 35-40° API and boiling in the range of 400-750° F., it is unnecessary to employ supplementary oxygen-containing gas and/or supplementary diluent to effect complete removal of consequent depositions of carbonaceous matter. In such a case the effluent gas of said catalyst regeneration, initially comprising nitrogen, carbon dioxide, and steam, as aforescribed, and subsequently comprising in addition to aforesaid, a gradually increasing content of oxygen as aforescribed provides thereby the necessary quantity of oxygen for removal of said carbonaceous deposit and a sufficient quantity of diluent to maintain the proper aforesaid ratio of diluent and oxygen, such that the carbonaceous deposits will be completely removed from the secondary heater within the duration of the catalyst regeneration.

20 In any instance, said effluent gas of catalyst regeneration can be used independently of supplementary oxygen-containing gas, by extending said burn-out to twice or even several times the duration of the catalyst regeneration period, supplying thereby the required quantity of oxygen and diluent for the complete burn-out of said secondary heaters.

25 Oxygen-containing gas, supplemental to the effluent gas of the catalyst regeneration supporting the burn-out or combustion of the carbonaceous deposits within the secondary heaters, as aforescribed, can be introduced through valve 68 to line 47. Supplementary diluent gas can be introduced through valve 66 to line 47.

30 When the deposition of carbonaceous material upon the inner walls of the tubes comprising the coil in heater 15 becomes such as to necessitate reconditioning the tubes, i. e. removing the accumulated deposits therefrom, the removal of carbonaceous deposits in heater 55 previously serving to heat primary preheater effluent to the conversion temperatures, aforescribed, has been completed.

35 Reconditioning of the tubes in secondary heater 15 is initiated subsequent to diversion therefrom of preheater 9 effluent and introduction thereto of aforesaid effluent catalyst regeneration gas, supplemented with another oxygen-containing gas and/or another diluent if desired, by means of passing effluent regeneration gas of catalyst chamber 43 to the spent gas stack through lines 44, 47 and 48 and valves 46 and 49 with valves 45, 34 and 51 closed, passing effluent of primary preheater 9 to secondary heater 55 through line 11 and valve 54 with valves 53 and 12 closed, passing effluent of secondary heater 55 to catalyst chamber 31 through lines 56, 64, 62, 25 and 30 and valves 61, 65 and 27 with valves 60, 24, 28 and 42 closed, and passing effluent of catalyst chamber 31 to a separation means 70 as aforescribed. Heater 15 is then purged with

steam introduced to line 47 through valve 66 and passed through valve 14 and line 13, with valves 53 and 12 closed, the effluent therefrom being passed to the spent gas stack through line 16, valves 47 and 58 and line 57 with valves 18 and 60 closed. Subsequent to a brief purge period thereof, the flow of catalyst combustion regeneration gas is diverted from catalyst chamber 43 directly to heater 15 by closing valve 40 with valve 39 open and passing said regeneration gas through lines 41 and 13 and valves 52 and 14 with valves 51, 53 and 12 closed, and passing the effluent gas therefrom to the spent gas stack through lines 16 and 57 as aforescribed. The flow of hydrocarbon effluent of heater 55 is then diverted from catalyst chamber 31 to catalyst chamber 43 by closing valve 27 with valve 42 open, and passing said effluent through line 41. The effluent of catalyst chamber 43 is then passed to a separation means 37 through line 44 and valve 45 with valves 46 and 33 closed. Catalyst chamber 31 is then purged with steam introduced through valve 67 to line 38 with valves 27 and 28 closed. Effluent purge gas is passed to the spent gas stack through lines 32, 41 and 43 and valves 34 and 49 with valves 33, 46 and 51 closed. Subsequent to a brief purge period thereof, the flow of catalyst combustion regeneration gas is diverted from heater 15 directly to catalyst chamber 31 by opening valve 28 with valves 27, 67, 39 and 49 closed and passing said regeneration gas through line 38. Effluent catalyst combustion regeneration gas of chamber 31 is then passed to heater 15 through line 32 and valve 34 through line 47 with valves 33 and 46 closed, splitting in part through line 43 and valve 49 to spent gas stack 50 and continuing in remaining part through lines 47, 48 and valves 51, 52 and 14 with valves 39, 53 and 12 closed. Supplementary oxygen-containing gas can be introduced to line 47 through valve 68 and supplementary diluent, such as steam, can be introduced through valve 66 to line 47. Effluent combustion gas of heater 15 is passed to spent gas stack 50 through line 57 by means aforescribed.

Similarly, preheater 9 effluent is subsequently switched back to secondary heater 15, heated therein and converted in catalyst chamber 31, while the fouled catalyst in chamber 43 is regenerated and carbonaceous deposits removed from secondary heater 55.

The aforescribed switch is effected intermittently, and comprises thereby, a continuous means of heating the hydrocarbon charge to the catalytic conversion process, without an interruption to the catalytic conversion that would result normally from an accumulation of carbonaceous deposits within the heating tubes, for example, an impairment of fluid flow by virtue of a reduced cross-sectional area of said tube and a less efficient heat transfer through the tube walls.

The cycles of the aforescribed catalyst regeneration and burning out procedures, are of the same duration. However, it is not to be understood that this invention is limited thereby as it is obvious that catalyst regeneration and secondary heater burn-out cycles aforesmentioned, can operate independently of each other.

It is not intended that the representation of the equipment as shown in the accompanying drawing be limited to any specific type used in a specific process, for the method of the invention is applicable to any of the many types of

heating arrangements used in catalytic conversion processes of hydrocarbon fluids.

My invention is illustrated and described in terms of a fixed bed catalyst. However, it is to be understood that my invention is not to be limited thereby, for it can be practiced in any catalytic hydrocarbon conversion process wherein in the formation and deposition of carbonaceous materials on the surface of the catalyst is concomitant with conversion of said hydrocarbon, inactivating said catalyst thereby, and wherein the activity of the catalyst is regenerated by the removal of said carbonaceous material by means of a combustion or burn-out, as for example, a hydrocarbon conversion process employing a fluidized catalyst.

Having fully described my invention, I claim:

1. An improved process for continuously heating and converting a hydrocarbon oil having a gravity in the range of 35 to 40° A. P. I. and boiling in the range of 400 to 750° F., in the presence of a granular fixed bed catalyst requiring regeneration by a combustion with an oxygen-containing gas, which comprises continuously preheating a stream of said oil to a temperature below that at which carbonaceous materials deposit from said stream; passing said preheated hydrocarbon stream to one of a plurality of secondary heating zones and further heating same therein to a temperature in the range of that required by subsequent conversion, with concomitant deposition of carbonaceous materials; passing the thus heated hydrocarbon stream to one of a plurality of catalytic reaction zones containing an active granular fixed-bed catalyst wherein said hydrocarbon is converted, said catalyst becoming progressively inactive by formation and deposition of carbonaceous materials on the surface thereof; passing effluent of said catalyst zone to a separation means, subsequently heating said preheated stream of oil in another of said plurality of secondary heating zones to said conversion temperature, passing the hydrocarbon stream to another of said plurality of said catalytic reaction zones and converting same therein and passing resulting effluents to said separation means, simultaneously passing regeneration gas containing from 5 to 20 per cent free oxygen to the inactive catalyst in the first said catalytic reaction zone in a direction concurrent with the aforesaid flow of oil being cracked, and under conditions effecting removal of carbonaceous material deposited thereon and producing effluent regeneration gas from first said catalytic reaction zone initially containing no free oxygen and subsequently containing free oxygen unreacted during said regeneration in progressively increasing concentrations until when carbonaceous matter is substantially completely removed from the surface of said inactive catalyst the oxygen content of said effluent regeneration gas is substantially the same as that of said regeneration gas being passed into first said catalytic reaction zone; passing total effluent regeneration gas from said first catalytic reaction zone through the first said secondary heating zone without admixing supplemental oxygen therewith and without admixing a diluent gas therewith in a direction concurrent with the aforesaid flow of oil being heated under conditions effecting reaction of oxygen with carbonaceous materials deposited therein; and removing from the system residual carbonaceous deposits from said first secondary zone as combustion product.

2. An improved process for continuously heat-

ing and converting a hydrocarbon oil having a gravity in the range of 35 to 40° A. P. I. and boiling in the range of 400 to 750° F., in the presence of a granular fixed bed catalyst requiring regeneration by a combustion with an oxygen-containing gas, comprising continuously preheating a stream of said oil in a primary preheater zone to a temperature below that at which carbonaceous materials deposit from said stream, passing preheated hydrocarbon stream from said primary preheater zone to a first secondary heater zone and therein further heating same to a temperature in the range of that required by the subsequent conversion, with concomitant deposition of carbonaceous materials; passing the thus heated hydrocarbon stream to a first catalytic cracking zone containing a fixed bed of active granular bauxite catalyst wherein said hydrocarbon is converted, said catalyst becoming progressively inactivated by formation and deposition of carbonaceous materials on the surface thereof; passing effluent of said first catalyst zone to a separation means; subsequent to said catalyst becoming inactivated, terminating the flow of heated hydrocarbon from said primary preheater to said first secondary heater zone and passing said heated hydrocarbon to a second secondary heater zone and therein heating same to the temperature required by said conversion; passing the hydrocarbon stream thus heated in the secondary hydrocarbon zone to a second catalytic reaction zone containing an active granular fixed bed catalyst of the kind contained in said first catalytic zone and therein converting said hydrocarbon and passing resulting effluents to said separation means; concurrent with converting hydrocarbons in said second catalytic zone admixing air with steam to produce a resulting steam-air admixture containing at least five volume per cent oxygen and passing the resulting steam-air admixture through the inactivated bauxite catalyst bed in said first catalytic zone in a direction concurrent with the aforesaid flow of oil being cracked and therein regenerating inactivated catalyst by

burning carbonaceous deposits free from the catalyst surface; effluent regeneration gas of said first catalytic zone initially containing no free oxygen and subsequently containing oxygen unreacted during said regeneration in progressively increasing concentrations until when carbonaceous matter is substantially completely removed from the surface of said inactive catalyst the oxygen content of said effluent regeneration gas is substantially the same as that of said steam-air admixture being passed into said first catalytic reaction zone; concurrent with heating hydrocarbons in said second secondary heater zone passing said effluent regeneration gas from said first catalytic zone, initially containing no free oxygen and subsequently containing oxygen, through said first secondary heater zone in a direction concurrent with the aforesaid flow of oil being heated without supplementing same with oxygen and without supplementing same with inert diluent, and burning free said carbonaceous deposits therein; and discharging all the gaseous effluent from said concurrent flow of regeneration gas through said secondary heater zone.

3. The process of claim 2 wherein said hydrocarbon oil is heated to a temperature below about 900° F. in said primary preheater zone and to a temperature in the range of 900-1300° F. in each said secondary zones.
